DESIGN FOR A BRACELET OR SIMILAR ARTICLE

William W. Hobe, New York, N. Y.

Application April 11, 1946, Serial No. 128,485

Term of patent 7 years

(Cl. D45—4)

To all whom it may concern:

Be it known that I, William W. Hobe, a citizen of the United States of America, residing in New York city, county of New York, and State of New York, have invented a new, original, and ornamental Design for a Bracelet or Similar Article, of which the following is a specification, reference being had to the accompanying drawing forming part thereof, wherein, or similar article showing my new design, the repeating units of which are disclosed in dotted lines for convenience of illustration.

Figure 2 is an edge elevational view of the bracelet or similar article shown in Figure 1.

I claim:

The ornamental design for a bracelet or similar article, substantially as shown and described.

WILLIAM W. HOBE.
